E. J. HAMER.

SANITARY PAPER WRAPPER FOR ICE CREAM CONES.

APPLICATION FILED DEC. 13, 1920.

1,403,771.

Patented Jan. 17, 1922.

UNITED STATES PATENT OFFICE.

ERNEST JOSEPH HAMER, OF LOS ANGELES, CALIFORNIA.

SANITARY PAPER WRAPPER FOR ICE-CREAM CONES.

1,403,771.

Specification of Letters Patent. Patented Jan. 17, 1922.

Application filed December 13, 1920. Serial No. 430,364.

To all whom it may concern:

Be it known that I, ERNEST JOSEPH HAMER, a citizen of the United States, residing at Los Angeles, in the county of Los Angeles and State of California, have invented a new and useful Improvement in Sanitary Paper Wrappers for Ice-Cream Cones, of which the following is a specification.

10 It is the object of the invention to provide a sanitary wrapper for ice cream cones and the like, which may be applied to the cone at the factory at the time of making the same, in order that the cone need not be 15 subsequently touched by the hands.

More specifically the invention contemplates the provision of a wrapper which may be made of paper or the like, and which may be readily wrapped around a cone, and 20 at the same time provide means for engaging the same so as to hold the wrapper in position.

The cone engaging means consists of tabs formed upon the wrapper and arranged to 25 be folded within the cone, and one of said tabs is formed with an extension arranged to project from the cone, so that by grasping the same, the tabs may be readily withdrawn from the cone when it is desired to 30 fill the latter with ice cream or the like.

The invention will be readily understood from the following description of the accompanying drawings, in which:

Fig. 1 is a plan view of the blank comprising the wrapper.

Fig. 2 is a side elevation showing the wrapper partially folded around an ice cream cone.

Fig. 3 is a similar view showing the cone 40 encased in the wrapper.

The improved wrapper is particularly adapted to be employed in connection with an ice cream cone such as is shown at 1 in dotted lines, but it will be obvious that the 45 invention is not limited to this particular application.

The wrapper is a blank such as shown in Fig. 1, and is preferably formed of paper. It is substantially a sector of a circle and 50 has the side edges 2 and 3 and the curved edge 4. The blank is wrapped around the cone, with edge 4 at the mouth of the cone, and the side edges 2 and 3 overlapping as clearly shown in Fig. 3.

55 The side edge 3 which is received against the cone, is preferably elongated at the apex

of the sector in order to form the lip 5, and after the blank has been wrapped into position, this lip is twisted around the bottom of the cone and its wrapper, in order 60 to hold the latter in position.

The wrapper may be further held in position by means of a usual gummed tab 6 upon the side edge 2, and adapted to be stuck to the wrapper when the same is in position; 65 or if desired the edge 2 may be pasted to the wrapper throughout its length, as soon as the latter has been wrapped around the cone.

At each end of edge 4 of the wrapper 70 blank, the latter is extended so as to form ears 7 and 8 projecting radially beyond the sector forming the blank; and at the junction of ear 8 at side edge 3 and the upper edge 4, an extension 9 of the blank is arranged beyond the edge 4 so as to extend part 75 way along the same.

When the wrapper blank is placed upon a cone, the ear 8 is folded down into the cone as clearly shown in Fig. 2, and extension 9 80 is allowed to remain projecting beyond the mouth of the cone. The blank is then wrapped into position and secured as previously described, and the ear 7 is then folded down into the cone over the ear 8, as 85 shown in Fig. 3. The cone is thus held against displacement from its wrapper, and the projecting extension 9 forms a convenient handle, which when drawn away from the cone will withdraw the folded ears 7 90 and 8 so that the cone may be filled.

It will be noted that the wrapper as thus described forms a sanitary covering for the cone, but at the same time is so arranged that the folded ears may be readily withdrawn in 95 order to place the cone in condition for use.

In practice the wrappers will be applied to the cones as they are made, and the latter may then be nested in usual manner for transportation. In using a cone, after withdrawing the folded ears in order that the cone may be filled, the ears may be torn off and thereby leave the cone with a protecting cover while the filler is being eaten; and this cover may be subsequently torn 105 away as desired.

It will be apparent that various changes may be made in the construction as thus described without departing from the spirit of the invention.

110 What is claimed is:

1. A wrapper for an article having an

- open end with projecting tabs at the respective sides of the wrapper adapted to be folded within the encased article.
2. A wrapper for an article having an open end with projecting tabs adapted to be folded within the encased article, one of said tabs having an extension forming a handle for withdrawing said folded tabs.
3. A protecting covering comprising a blank adapted to be wrapped around an article, and having projecting tabs at each side of said wrapped covering arranged to be folded within the encased article.
4. A protecting covering comprising a blank adapted to be wrapped around an article and having projecting tabs at each side of said wrapped covering arranged to be folded within the encased article so as to overlie one another.
- 20 5. A protecting covering comprising a blank adapted to be wrapped around an article and having projecting tabs at each side of said wrapped covering arranged to be folded within the encased article so as to overlie one another, and an extension upon the under tab projecting outwardly and forming a handle.
6. A protecting covering comprising a blank adapted to be wrapped around an article with the lower end of the blank having an extension twisted over the end of the article so as to retain the cover in position.
7. A protecting covering comprising a blank adapted to be wrapped around an article with the lower end of the blank twisted over the end of the article so as to retain the cover in position, the upper end of said blank having projecting tabs at the respective sides thereof adapted to be folded with- in the encased article.
8. A protecting covering for a tapering article comprising a sector - shaped blank adapted to be wrapped around the article and having a projecting lip for securing the free edge of said blank to the same.

ERNEST JOSEPH HAMER.
